UNITED STATES PATENT OFFICE.

SWAN O. WIDELL, OF ROCKFORD, ILLINOIS.

DESIGN FOR A WIRE-STRETCHER.

51,912.

Specification for Design. Patented Mar. 26, 1918.

Application filed October 5, 1917. Serial No. 194,994. Term of patent 7 years.

To all whom it may concern:

Be it known that I, SWAN O. WIDELL, a citizen of the United States, residing at Rockford, in the county of Winnebago, and State of Illinois, have invented a new, original, and ornamental Design for Wire-Stretchers, of which the following is a specification, reference being had to the accompanying drawing, forming a part thereof.

In the drawing—

The figure is a perspective view of a wire stretchers showing my new design.

I claim:

The ornamental design for a wire stretcher, as shown.

SWAN O. WIDELL.
